(57) CLAIM

The ornamental design for a door knob with lock and illumination, as shown and described.

DESCRIPTION

FIG. 1 is a front, top, and left side perspective view of a door knob with lock and illumination;

FIG. 2 is a front, top, and right side perspective view thereof;

FIG. 3 is an elevational front view thereof; and,

FIG. 4 is an elevational side view thereof.

The broken lines shown are for illustrative purposes and form no part of the claimed design.
